UNITED STATES PATENT OFFICE.

WILLIAM FRANK TAYLOR, OF CHARLESTON, SOUTH CAROLINA, ASSIGNOR TO GENERAL ASBESTOS & RUBBER COMPANY, OF CHARLESTON, SOUTH CAROLINA.

GASKETING-TAPE.

1,108,021.

Specification of Letters Patent.

Patented Aug. 18, 1914.

Application filed February 28, 1914. Serial No. 821,798.

To all whom it may concern:

Be it known that I, WILLIAM F. TAYLOR, of Charleston, in the county of Charleston and State of South Carolina, have invented 5 certain new and useful Improvements in Gasketing-Tapes; and I do hereby declare the following to be a full, clear, and exact description of the invention, such as will enable others skilled in the art to which it 10 appertains to make and use the same.

This invention relates to gasketing tape and more particularly to such as are adapted for use as packing for steam boilers, cylinder heads, flanges and the like,—the object 15 of the invention being to provide a flat gasketing tape which may be marketed as such and which shall be readily adaptable for making packings of any desired size and shape and which, when bent into circular 20 form, will provide an efficient joint without the use of additional connecting means.

With this and other objects in view, the invention consists in certain novel features of construction and combinations of parts as 25 hereinafter set forth and pointed out in the claims.

In the accompanying drawings; Figure 1 is a view of a straight section of my improved tape; Fig. 2 is a view showing the 30 tape bent to form a circular gasket section with the flat faces of the tape in horizontal planes and the ends joined; and Fig. 3 is a view of the tape bent to form a circular packing with the flat faces of the tape disposed vertically.

My improved tape comprises two members 1 and 2, each of which is constructed of woven asbestos fiber and wire. The member 1 is made in the form of a flat tube and the 40 member 2 of the same material, is a flat strip inclosed by the flat tubular member 1 and constitutes a core which is movable lengthwise in the latter for a purpose hereinafter explained.

45 In constructing the flat tubular member 1, I take an elongated strip of wire-reinforced woven asbestos and fold the same lengthwise upon itself so as to inclose the flat core member 2. The two free edges 50 are then folded in upon themselves as indicated at 3 and the two edges are then

stitched together as shown at 4. By constructing the flat tape of woven asbestos as above described, both the tubular member and the flat core are flexible and may 55 be readily bent in either of two directions. That is to say, the tape may be bent edgewise into circular form with its flat faces disposed in horizontal planes, as shown in Fig. 2, or said tape may be bent into circular form with its flat faces disposed vertically. In either case, the tape will maintain its flat form and may be used in formation of gasket members of any desired size and number, according to the particular 60 requirements in any given case.

The ends of a section of the tape will preferably be cut diagonally and the flat flexible core member 2 will be pulled longitudinally through the covering member 1 until one 70 end of said core projects beyond one end of the tubular covering 1, thus forming a tongue 5 which may enter the pocket 6 formed in the other end of the member, 1. In this manner, the two ends of the tape forming 75 a circular gasket member may be joined without the use of added connecting means. If desired the joint formed as above described may be formed with binding or tire tape 7 as indicated in Fig. 2.

Having fully described my invention what I claim as new and desire to secure by Letters-Patent, is:—

1. A flat gasketing tape comprising a flat elongated envelop of woven asbestos and a 85 flat core of woven asbestos inclosed within said flat envelop and movable longitudinally of the same.

2. A flat gasketing tape comprising a strip of woven asbestos folded upon itself 90 and stitched along the meeting edges forming a flat elongated envelop, and a flat woven asbestos core inclosed by said envelop and movable longitudinally of the same.

In testimony whereof, I have signed this specification in the presence of two subscribing witnesses.

WM. FRANK TAYLOR.
